(57) **CLAIM**

The ornamental design for a shower-type basketball game, as shown and described.

DESCRIPTION

FIG. 1 is a front perspective view of a shower-type basketball game showing my new design;

FIG. 2 is a right side elevational view thereof;

FIG. 3 is a left side elevational view thereof;

FIG. 4 is a front elevational view thereof;

FIG. 5 is a rear elevational view thereof; and,

FIG. 6 is a top plan view thereof.

The items shown in dashed line are not part of the claimed invention.
